UNITED STATES PATENT OFFICE

2,510,832

STORE FRONT

Chester A. Patterson, Milwaukee, Wis., assignor
to Jos. Schlitz Brewing Company, Milwaukee,
Wis., a corporation of Wisconsin

Application May 2, 1946, Serial No. 666,639

2 Claims. (Cl. 20—40.4)

1

This invention relates to store fronts and refers particularly to a prefabricated store front adapted for application to the existing front of a building to improve the appearance thereof without the necessity of, or with a minimum in any case, of structural changes to existing conditions.

There are many instances where it is desired to "dress up" or improve the appearance of an existing building front, but where the cost of remodeling structurally would not be warranted. Chain stores and similar multi-unit organizations are often confronted with the need for making substantial modifications to existing buildings in order to maintain the chosen store-front pattern or design.

The present invention makes possible the achievement of these objectives at a minimum cost, and with this point in mind it is the chief object of this invention to provide a novel manner of producing a complete change to an existing store front without structural changes and which permits prefabrication of its component parts as stock units easily and quickly adapted to be assembled and mounted in position and to cover any width, height, return or angle.

With the above and other objects in view which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claims and to fit varying conditions.

The accompanying drawings illustrate one complete example of the physical embodiment of the invention constructed in accordance with the best mode so far devised for the practical application of the principles thereof, and in which:

Figure 1 is a front perspective view of a prefabricated and fully erected store front embodying this invention, part thereof being broken away to illustrate structural details;

Figure 2 is an end view of the upper portion of the store front shown in Figure 1;

Figure 3 is an exploded perspective view showing the several parts which make up the prefabricated store front, separated and in their proper order of assembly;

Figure 4 is a vertical sectional view through Figure 1 on the plane of the line 4—4; and

Figure 5 is a fragmentary detail view illustrat-

2

ing one manner in which variation in the width of the building front may be readily accommodated.

Referring now more particularly to the accompanying drawings, the numerals 5 and 6 indicate a pair of window sections each having a window 7. These window sections are upright units each adapted to cover a portion of the front of the existing building. In the embodiment of the invention illustrated, there are two or more pairs of individual window sections arranged at opposite sides of an entrance door 8 and the entrance door, as is often the case in store fronts, is recessed rearwardly of the plane of the store front.

The window sections 5 and 6 are prefabricated stock units provided in several standard widths of sash within an inch or fraction thereof more or less. Hence, any store front regardless of its height or width can be covered with an appropriately chosen number of such sections. Fractional differences which cannot be accommodated in this manner can be adjusted by interposing a mullion or mullions 10 of varying standardized prefabricated width or widths and design between window sections 5 and 6 as shown in Figure 5. The window sections are placed against the existing glass or other front and are removable to enable washing the existing windows.

The window sections are flanked by blind sections 11. These blind sections, while prefabricated as stock units, can be supplied in different widths to thus further accommodate variations in store front widths.

Predetermined positional relationship between the blinds and the window sections is achieved by interengaging means on these parts, as for instance dowel pins 12 on the upper corners of the window sections engaging in notches 13 in the upper edges of the blinds. Each blind has two such notches so that it may be mounted either at the right or the left of a window section.

Where the entrance door is recessed as illustrated, the sides of the entranceway must, of course, also be covered and for this purpose additional window sections 14 are provided, together with mullions and other parts as may be necessary to exactly fit and follow the contours of said entrance ways, and these window sections 14 together with such mullions as may be necessary are of a composite size to completely cover the sides of the entrance way, and like sections 5 and 6 have windows 15 therein.

In the application of the store front to an

existing building, the upright window sections 5, 6 and 14 may be secured in position in various ways as for instance, by being suspended from a suitable supporting frame work 16 furred out from the front of the existing building, with hooks 17 secured to the window sections.

The window sections 5, 6 and 14 may or may not have their lower edges terminate at or above the sidewalk as existing conditions and restrictions may require. Where they terminate above the sidewalk, the space therebeneath may be covered by a bottom section 18. This bottom section may take any desired form to suit different designs, but in the present illustrated design it is a box-like unit having front and back walls 19 and 20 and bottom and top walls 21 and 22 respectively. These bottom sections, in an arrangement such as that illustrated where the door is centrally located, are paired with the adjacent ends thereof formed as flower boxes 23 and provided with rearward angularly disposed extensions 24. This bottom treatment may vary to accord with the varying types of architecture and to regulate the required height between sidewalk and window areas.

The bottom sections are of a height to cover the lower portions of the window sections 5 and 6 and to have the blinds 11 rest thereon. Preferably, also a supporting strip 25 fixed to the window sections 5 and 6 rests on the bottom sections.

Securement of the bottom sections in place locks the window sections 5 and 6 in position and while such securement of the bottom sections may be effected in different ways, it is conveniently done by bolts 26 passed through a bottom rail 27 of the frame work 16, through apertures 28 in the window sections 5 and 6, and through the back wall 20 of the box-like bottom section. Inside the box, nuts 29 threaded on the bolts 26 hold the parts together.

The blinds 11, inasmuch as they overlap the window sections, do not themselves extend in back of the bottom sections but may have tongues 30 projecting downwardly therefrom to engage behind the bottom sections so that the blinds are also secured against outward displacement by the bottom sections.

Attention is directed to the fact that the rearward triangular extensions 24 engage the adjacent portions of the window sections 14 and thus serve to hold these members in place upon securement of the bottom sections in position.

The top of the structure is completed by a telescoping panel unit or head piece indicated generally by the numeral 31. This unit consists of two end panels 32 and a center panel 33. The end panels are stock lengths which vary in multiples of two feet and are so chosen that their combined length is shorter than the full width of the front. The center panel 33 is of a length to span any space between the end panels. Thus through the selection of end panels of proper length it is possible to fit the panel unit 31 to any width of store front and always have desirable symmetry.

The entire top unit is so located that it covers the upper portions of the upright window sections 5 and 6 as well as the upper ends of the blinds 11 and thus not only completes the design but holds the blinds in position. The top panel unit is rigidly bolted and countersunk and secured to the building wall in any suitable manner and to preclude the entrance of rain and dirt between it and the existing front of the building, the space between the top panel section and the building is closed by suitable sheet metal flashing 34 fixed to the building and to the top panel unit as shown in Figure 2.

As can be readily appreciated the telescoping top panel unit in addition to finishing off the design can be used to cover existing glass areas where tall old-fashioned windows exist in order to obtain a better scale and feeling to said front design if so desired.

From the foregoing description taken in connection with the accompanying drawings it will be readily apparent that this invention makes possible quick and inexpensive transformation of an ordinary store front into a pleasing, pre-determined design, and at a cost much less than would be required to make an actual structural change.

What I claim as my invention is:

1. A prefabricated false front for buildings to improve the appearance thereof, comprising a plurality of upright window sections; means on said window-sections for suspending the same in side-by-side relation in front of the existing window or windows of the building; upright panel sections adjacent to the window sections and substantially the same height as the window sections; cooperating means on said panel and window sections for holding said sections in side-by-side relation; telescoping members defining an elongated, extensible top panel extending across the upper portions of said sections and coacting with said cooperating means to hold the sections together at the top; and a bottom section extending across the lower portions of said panel and window sections to hold the same together at the bottom.

2. The false front set forth in claim 1 further characterized by the fact that said panel and window sections are connected together in overlapping relation by said cooperating means which holds the panel and window sections in side-by-side relation.

CHESTER A. PATTERSON.
